DISPENSING FAUCET FOR A COFFEE URN OR THE LIKE

Alfred H. Brundage, Maplewood, N. J.

Application October 28, 1957, Serial No. 48,253

Term of patent 14 years

(Cl. D2—3)

Fig. 1 is a perspective view of a dispensing faucet for a coffee urn or the like embodying my design;

Fig. 2 is a top plan view thereof; and

Fig. 3 is a side elevational view thereof.

I claim:

The ornamental design for a dispensing faucet for a coffee urn or the like, as shown.
